(57) **CLAIM**

The ornamental design for a lid for bottle as shown and described.

DESCRIPTION

FIG. 1 is a top, front, right perspective view of a lid for bottle showing my new design in a closed configuration.

FIG. 2 is a bottom, rear, left perspective view thereof.

FIG. 3 is a front view thereof.

FIG. 4 is a rear view thereof.

FIG. 5 is a top view thereof.

FIG. 6 is a bottom view thereof.

FIG. 7 is a left view thereof.

FIG. 8 is a right view thereof.

FIG. 9 is a top, front, right perspective view of the lid for bottle shown in an open configuration.

FIG. 10 is a bottom, rear, left perspective view thereof.

FIG. 11 is a front view thereof.

FIG. 12 is a rear view thereof.

FIG. 13 is a top view thereof.

FIG. 14 is a bottom view thereof.

FIG. 15 is a left view thereof.

FIG. 16 is a right view thereof; and,

FIG. 17 is a top, front, right perspective view of the lid for bottle of FIG. 1, shown in an environment of use.

The broken lines showing a bottle in FIG. 17 illustrate environmental structure. All other broken lines illustrate portions of the lid for bottle. The broken lines form no part of the claimed design.

1 Claim, 17 Drawing Sheets
